(57) CLAIM

The ornamental design for a tool for sealing a resealable zipper lock bag, as shown and described.

DESCRIPTION

FIG. 1 is an upper front perspective view of a tool for sealing a resealable zipper lock bag;

FIG. 2 is a lower rear perspective view thereof;

FIG. 3 is a left side view thereof;

FIG. 4 is a rear view thereof;

FIG. 5 is a right side view thereof;

FIG. 6 is a front view thereof;

FIG. 7 is a top view thereof; and,

FIG. 8 is a bottom view thereof.

The broken lines shown in the drawing depict environmental subject matter only and form no part of the claimed design.
